FIG. 1.

FIG. 2.

FIG. 3.

Inventor:

Emilio Lüling & Mario Baroni

per

H. W. Puecker

Attorney.

UNITED STATES PATENT OFFICE.

EMILIO LÜLING AND MARIO BARONI, OF MILAN, ITALY.

BEAM, GIRDER, OR THE LIKE.

1,390,364.

Specification of Letters Patent. Patented Sept. 13, 1921.

Application filed March 27, 1917. Serial No. 157,776.

To all whom it may concern:

Be it known that we, EMILIO LÜLING and MARIO BARONI, both subjects of the King of Italy, residing, respectively, at 7 Via Principe Umberto and 21 Fatebenefratelli, both in Milan, in the Kingdom of Italy, have invented certain new and useful Improvements in Beams, Girders, or the like, of which the following is a specification.

- 10 This invention relates to an improvement in the construction of beams or girders, and is especially applicable to the construction of reinforced concrete beams. It enables the moment of resistance of a given part of the 15 core or longitudinal reinforcement of a beam, that is to say, the moment of resistance of the total section of the iron bars, (whether round or square or of any other section), of which it consists, to be increased.
- 20 This is effected by dividing the area of the said section into several parts, while the value of the sum of the various partial areas resulting from this division is equal to the original area.
- 25 This result is obtained, according to the invention, by forming a core with members (iron bars, round or square or of any other shaped section) kept apart by spacing members which bind them rigidly together by 30 friction.

The accompanying drawing shows a constructional example of the invention.

Figures 1, 2 and 3 show a cross-section, a longitudinal view and a plan respectively of 35 a beam core consisting of eight rods of round section connected together by screw bolts.

The cores may be employed singly as gird-

ers, or they may be used to constitute either the upper or the lower members, or both, of compound metal frames designed to withstand tension stresses in ferro-concrete structures.

In the form shown on the drawing the eight bars *a'* are rigidly connected together by means of threaded bolts *b'* provided with 45 nuts *c'*, said bolts being disposed vertically and horizontally in alternating sequence, and gripping the bars in two directions at right angles to one another. The elements comprising this structure can be readily assembled and taken apart.

What we claim and desire to secure by Letters Patent of the United States is:—

A structural element more particularly adapted for use in a reinforced concrete 55 structure, comprising a plurality of longitudinal beams arranged in horizontal and vertical rows, transverse bolt members arranged at right angles to each other and interposed alternately between the horizontal 60 rows and between the vertical rows of beams and having their thickness designed so as to determine all the spaces between the beams, and bolt heads and nuts on the bolt members for engaging the beams and retaining same 65 in spaced position and against the sides of the bolt members.

In testimony whereof we affix our signatures in presence of two witnesses.

EMILIO LÜLING.
MARIO BARONI.

Witnesses:

OTTORINO LARRARI,
IVAN LAVRETSKY.
